UNITED STATES PATENT OFFICE.

CHARLES D. BARRETT, JOHN E. MYERS, AND ALBERT O. KING, OF ALTOONA, PENNSYLVANIA.

BALANCED THROTTLE-VALVE.

1,386,678.

Specification of Letters Patent. Patented Aug. 9, 1921.

Application filed September 16, 1920. Serial No. 410,726.

To all whom it may concern:

Be it known that we, CHARLES D. BARRETT, JOHN E. MYERS, and ALBERT O. KING, citizens of the United States of America, and 5 residents of Altoona, county of Blair, State of Pennsylvania, have invented certain new and useful Improvements in Balanced Throttle-Valves, of which the following is a true and exact description, reference being 10 had to the accompanying drawings, which form a part thereof.

Our invention relates to throttle valves such as are used in connection with locomotive engines and in which the throttle valve 15 is more or less approximately balanced by a balancing piston and cylinder. As heretofore constructed it has been found that in opening the valve and in certain conditions of use it is very difficult and requires a great 20 deal of power to move the valve from a position in which it is partly opened to a more open or fully opened position and this difficulty we have found to arise by reason of the application of a thin jet of steam when 25 the valve first leaves its seat, which steam jet impinges upon the balancing piston with sufficient force to unbalance the valve and make it very difficult to move it from its seat. The object of our invention is to so 30 deflect this jet formed on the initial opening of the valve that it will no longer impinge upon the balancing piston in such a way as to unbalance the valve and our invention consists, broadly speaking, in inter- 35 posing a deflecting plate in the path of the jet which will prevent it from impinging on the piston in a manner to unbalance it.

The nature of our invention will be best understood as described in connection with 40 the drawings in which it is illustrated, and in which—

Figure 1 is a sectional elevation showing the throttle valve, its seat, balancing cylinder and piston and our improved deflecting 45 plate in what we believe to be its best and most efficient form of construction, and

Fig. 2 is a similar sectional elevation showing a modified form of application of our improved deflecting plate.

50 A indicates a dry pipe head having formed on it a seat A' for the throttle valve and formed in it, as shown, a cylindrical passage A² for the rod by which the valve is opened. B is the balancing cylinder; C is 55 the throttle valve having formed through it a steam passage which connects with the

balancing piston D. Said passage has a valve seat C² at its top and opens through the balancing piston. E is the pilot valve secured to the actuating stem E'. In all of 60 the above mentioned features the construction illustrated is of a generally familiar type.

As shown, we form the throttle valve C with a lip or flange C³ for a purpose we will 65 explain.

F is our improved deflecting plate which, as shown, is annular in form having its lower edge F² secured to the top of the balancing cylinder B and curving inward from this 70 edge so as to afford a clear steam space and upward at its upper edge so that its top F' lies nearly in contact with the top of the throttle valve when it is closed and nearly in contact with the flange C³. By this construction we leave as much as possible of 75 the under surface of the throttle valve in free communication with the space above the balancing piston, and maintain approximately the same pressure on the valve and 80 piston.

In Fig. 2 a indicates the top of the dry pipe, a' the seat for the throttle valve, a³ and a⁴ the steam passages, b the balancing cylinder, d the balancing piston, c the 85 throttle valve having the seat c² for the pilot valve. e is the pilot valve and e' the stem connected with the pilot valve for actuating it and the throttle valve. In these features, also, the construction is of a well known 90 type and needs no further explanation. indicates a deflecting plate which is shown here as connected to the valve seat directly below this seat portion and extends out so that when the throttle valve is slightly open 95 the steam jet will impinge against it and be deflected so as to impinge upon the throttle valve and its connections with the balancing piston in such a way that the energy of the jet will be so distributed that 100 it will not tend to unbalance the throttle valve.

The operation of the construction shown in Fig. 2 has been sufficiently explained. It is obvious with regard to the construction 105 shown in Fig. 1 that when the throttle valve is slightly open the jet will impinge upon the deflecting plate F and will not come in contact with the piston or any attachment to the piston. The reason for the curved 110 form given to the deflecting plate is to insure as far as possible that the pressure existing

2
upon the top of the piston will be the same as the pressure existing on the lower side of the throttle valve, and this purpose is obviously aided by forming the valve with the 5 lip C⁸ as described.

Having now described our invention, what we claim as new and desire to secure by Letters Patent, is:

1. In combination with a throttle valve 10 and a balancing piston attached thereto, a steam deflecting plate located in the steam passage between the valve and its piston so as to prevent the steam jet formed when the valve is first opened from so impinging on 15 the piston as to materially interfere with the balance of the valve.
2. In combination with a throttle valve and a balancing piston attached thereto, an annular steam deflecting plate extending 20 over the piston cylinder so as to prevent the impingement of the steam jet, formed when the valve is first opened, on the piston.
3. In combination with a throttle valve and a balancing piston attached thereto, an 25 annular steam deflecting plate supported on and extending over the piston cylinder so as to prevent the impingement of the steam jet, formed when the valve is first opened, on the piston.
4. In combination with a throttle valve 30 and a balancing piston attached thereto, an annular steam deflecting plate extending

over the piston cylinder to a height which will bring the top edge close to the closed valve, said deflecting plate having its sides 35 curved inwardly from the bottom and outwardly at its top so as to protect the piston from the impingement of the steam jet when the valve is first opened and maintain substantially constant pressure on the top 40 of the piston and the bottom of the valve.

5. In combination with a throttle valve having a lip, C⁸, and a balancing piston attached thereto, an annular steam deflecting plate extending over the piston cylinder, 45 said deflecting plate having its sides curved inwardly at the bottom and outwardly at the top and its top edge lying close to the lip on the valve, so as to protect the piston from the impingement of the steam jet when the 50 valve is first opened, and to form with the inner walls of the throttle valve a chamber nearly closed, so that the under side of the top wall of the throttle valve and the top of the balancing piston are subjected to the 55 same pressure and that the velocity of the steam passing through the throttle valve does not have an impact or suction action on their surfaces, resulting in an unbalanced action on the valve.

CHARLES D. BARRETT.
